UNITED STATES PATENT OFFICE.

JAMES F. FERGUSON, OF BURLINGTON, VERMONT.

CHURN.

SPECIFICATION forming part of Letters Patent No. 252,091, dated January 10, 1882.

Application filed January 14, 1881. (Model.)

To all whom it may concern:

Be it known that I, JAMES F. FERGUSON, a citizen of the United States, residing at the city of Burlington, in the county of Chittenden and State of Vermont, have invented certain new and useful Improvements in Churns; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to improvements in rotary churns; and it consists in a rotary body having placed in it a platform which is notched so as to fit the opening in the body, and which serves to guide the butter from the body into 20 a bowl or dish to receive it.

In the drawings, in which similar letters indicate like parts, Figure 1 is a perspective view. Fig. 2 is a vertical central section. Fig. 3 is a cross section. Fig. 4 is a view in perspective of the platform H.

A is the body of the churn. It is made of wood and of rectangular form, its width being less than the other dimensions.

B B' are the standards, supported by a suitable frame, in the upper extremities of which the gudgeons C C' are intended to revolve. To one of the gudgeons, C, a crank is attached. Through the side of the churn and the center of the other gudgeon, C', is an opening, D, for 35 the purpose of ventilation. The exterior ventilating-tube is the tube d, which terminates in a funnel at the top, the bottom being in the form of an elbow, which turns at right angles to receive the exterior end of the gudgeon C', 40 so as to form a continuous pipe from the interior of the churn to the flange at its top. This elbow rests upon a shoulder in the end of the standard B, the tube being held in a vertical position by the adjustable collar or spring-clamp E. This arrangement is sufficient, provided the surface of the cream is below the opening D. Should the churn be filled above that point, ventilation is secured by the addition of the two tubes e and f, which are firmly 45 connected together at right angles, the part e being of sufficient size and length to be passed

through the opening D in the churn and gudgeon C' and screwed into the elbow of the tube d, while the part f is designed to stand erect within the churn at a height sufficient to allow 55 the ventilating-cap g to be above the cream. Perfect ventilation to the interior of the churn is thus obtained under all circumstances without the possibility of the escape of the cream during the churning process. At the same 60 time the several parts employed can be so readily cleansed and adjusted that they are not liable to taint or derangement.

F is the entrance into the churn. It is hermetically closed by the glazed cover h by means 65 of a rubber packing and suitable exterior fastenings.

G is an automatic strainer, designed to be fitted into the interior end of the outlet i of the churn after the process of churning is completed, to prevent any particles of butter running off with the buttermilk or water.

H is a removable platform to assist in withdrawing the butter from the churn. It is somewhat longer and narrower than the interior of 75 the churn, and is so notched at one end that when in position this end projects a short distance beyond the opening F, to guide the butter into a butter-bowl placed to receive it.

In operation the grain of the butter is not 80 broken, as the interior of the churn presents no obstacles which produce friction to the cream, while the peculiar shape of the box, it being narrow in proportion to its other dimensions, confines the cream in a channel, thereby producing the greatest concussion and falling pressure during each revolution upon each particle of the cream alike with the smallest amount of power employed, thus causing the easiest and most complete separation possible. 85

This simple and reliable system of ventilation secures a free passage for the air into or out of the churn, so necessary to promote those chemical changes in the cream which are essential to the production of the best butter. 95

The entire device also admits of great ease and readiness in washing the butter and salting it before it is consolidated into large lumps, thus insuring the greatest uniformity as well 100 as the best texture and grain of the butter.

The removable platform H, being of less

width than the churn, allows the buttermilk to flow into the bottom of the churn, and permits the entire mass of the butter to be readily removed from the churn without any liability to injury from handling.

Having thus described my invention, what I claim, and desire to secure by Letters Patent, is—

In a rotary churn, the combination of the

revolving body A with the platform H, notched to fit the opening F in the top of the body, substantially as shown and described.

In testimony whereof I do affix my signature in presence of two witnesses.

JAMES F. FERGUSON.
